UNITED STATES PATENT OFFICE.

JULIUS CLINTON WRIGHT, OF WACO, TEXAS.

AIR TRANSFERRER.

Application filed August 21, 1924. Serial No. 733,449.

This invention relates to rotary air trans-
ferrers, and has for its principal object the
improvement generally of such mechanisms.

A second object of the invention is to so
5 design the base of the impeller or runner
and the passageway walls that the air or
other fluid shall be directed into the dis-
charge with minimum friction, the base be-
ing preferably a curved cone or conoid, and
10 the walls of the passageways rising from a
spiral drawn on the face of the conoid and
arched toward and beyond the periphery of
the conoid from which they are spaced to
provide the discharge exits.

15 A further object of the present invention
is to provide an improved rotary impeller
possessing valuable characteristics whereby
the efficiency of the complete blower is aug-
mented. A further object of the invention
20 is the provision of a blower in which the air
is trapped in each of a plurality of sym-
metrical and balanced air chambers in each
of which the area of the intake is in excess
25 of the area of the discharge orifices where-
by pressure is secured in the discharge of
the blower. A still further object of the
present invention lies in the provision of a
30 blower in which the number of vanes of the
impeller is prime with respect to the num-
ber of blades of the casing, that is, the num-
ber of vanes and the number of blades have
no common divisor except unity.

35 Various other objects of the invention re-
late to the specific details of construction of
the various parts and are set forth in detail
in the specification following and are partic-
ularly set forth in the claims.

40 All rotary transmitters, whether of the suc-
tion or the discharge type, run at a rather
low efficiency, and it is my desire to pro-
vide an air transmitter which by reason of
its design and shape will increase the effi-
45 ciency of these mechanisms. I secured this
much desired object by eliminating eddy
currents in the intake and by directing the
incoming air into the hooded mouths of the
passageway, preferably two in number al-
50 though three or more could be used if de-
sired.

55 In the drawings:

Figure 1 is a side elevation of a blower
embodimenting the features of my invention.

Figure 2 is a top plan view.

55 Figure 3 is a side elevation of the impeller
with the top wall broken away in part to
define more clearly the air channels.

Figure 4 is a cross section on line 4—4 of
Figure 3.

Figure 5 is a cross section on line 5—5 of
Figure 3.

Figure 6 is a perspective of the impeller
but omitting the air-lock ring.

Figure 7 is a cross section taken on the
face of the base.

Figure 8 is a detail of the corner of the
60 mouth of the hood.

In Figure 1, the invention is shown in a
specific embodiment as applied to a blower,
it being noted, however, that the invention
is applicable to suction fans and other

types. It will be understood by those
skilled in the art that when the fan shown as
a blower is to be used as a ventilator, the
base of the runner or impeller is cut away at
70 the periphery, and the blades are lengthened

in accordance with standard ventilator prac-
tice. The main shaft 10 is provided with
75 a thrust bearing 11 in the housing frame 12
and a second bearing 14 in a stationary part
of the blower as a whole, the shaft 10 be-
tween these two bearings preferably carry-
ing a pulley 15 from which the impeller re-
ceives its power. As would be apparent to
80 those skilled in the art, the pulley 15 is
merely diagrammatic, and may, in practice,
85 be a steam turbine or an electric motor,
either of these prime movers working effi-
ciently with the combination, especially in
view of the concave formation of the im-
peller base plate.

90 The housing has three arms 16 preferably
at 120° apart each arched to clear the im-
peller and each preferably having a fin 18
within the impeller to increase the efficiency
95 of the device. The duct 19 in the hous-
ing is circular in cross section and has a
constant minimum diameter but is eccentric
in that the cross section diameter gradually
increases to the eduction in discharge out-
100 let. In the specific embodiment shown, the
impeller has two hoods 17, so the combina-
tion of the two hoods or vanes with the
three arms or baffles of the housing, trap the
air very well and prevent absolutely all
105 throbbing due to the movement of the ro-
tary element. The discharge passageways
each constantly decrease in size throughout
its extent from entrance to exit and conse-
quently the entrance area is in excess of the
110 discharge area, resulting in a discharge pres-
sure since the speed of the air is increased in
passing thru the smaller area at discharge.

As will be seen from Figure 4, the base 20 of the rotary element or impeller is a surface of revolution of the type that may be called a curved cone, the cross section of the curve being such that it lies tangent to the axis at its point of contact therewith 21, and at a point near its outer edge, it begins to approach a plane at right angles to the axis of rotation of the shaft 10.

10 The apical portion of the base or cone is positioned centrally of the air intake and by virtue of its smooth and graceful curve, it deflects the air in the center of the moving column toward the two hoods 17. Each of 15 these hoods is in a plane substantially radial and my preference is that the two hoods shown shall be substantially diametrically opposite one another, although for practical reasons I find it preferable and more convenient to have the planes of the mouths of 20 the passageways parallel one to the other with a space of a few inches between them.

The area of each mouth 17 is very considerably larger than customary in the art, the 25 size or area of the mouth being determined entirely by the amount of pressure desired in the discharge, the height over all of the mouth in turn giving the pitch of the snail-like passageway to which each of the mouths 30 17 lead, such pitch being uniform through the length of the passageway.

The passageway which has its entrance at the hood 17 is defined on its inside by the spiral line 33 on the face of the base and at 35 its peripheral edge by the arc 34. The initial outer wall of each passageway rises substantially centrally of the tail end of the opposite passageway, as will be better understood from a consideration of Figure 4 wherein the space 37 is that portion of the intake divided off from the major passageway 38 by the dividing wall 39, and the passage 40 is the discharge end of the opposite 40 passageway 38. The wall 41 is substantially arch-shaped and merges at its outer edge 45 with the bell-like flare or skirt 42 of the impeller. When the impeller is whirled at full speed, it gives one the impression of a bell, the slope of the body proper being given by the wall 43, which, as previously 50 stated, has an evenly sloping outwardly flared bell mouth or skirt 42.

The secondary mouth 45 is placed slightly inward of the main mouth 17, and it, with 55 the wall 39, deflects a fourth of the total air received by the mouth 17 of the hood, through the orifice 46 between the terminal mouth 47 of the opposite snail-like passageway and the portion 48 at the end of the wall 39. The remainder of the air entrapped in the large mouth or hood 17 is carried 60 through the major portion of the constantly decreasing passageway and a portion of it is diverted by the wall 39 and delivered between the exits 51, 52, and 53 by means of 65

the relatively small diverting walls 54. It will be observed that each of the two passageways is identical in all respects and have consequently been given the same numerals. The discharge end of one passageway passes 70 under the other passageway only through a very small portion of its extent, namely, from the entrance 17 of the second passageway to the baffle or vane 47 of the passageway, this being an angle much less 75 than 90°.

It will be noted that the two hood mouths each lie substantially in a plane passing through the axis and they are therefore presented to the air to be trapped at right angles to the direction of movement of the mouth rim, and the downward and inward slopes of the walls of each of the whorls or snails is such that the least possible friction is added to the system; in other words, 80 these walls are of stream-line formation in so far as it is possible with the pitch determined by the amount of pressure desired. The center-line of the wall of the upper initial portion of each of the hoods is at an angle of 45° to both the horizontal and the vertical. Consequently, this wall guides the 85 trapped air into the passageway under it and the untrapped air into the adjacent passageway with minimum friction. Looking directly down upon the impeller, it will be seen that all surfaces are in substantially stream-line formation, directing the air through the nearest forwardly moving hood. The back of each hood is curved in arch formation from side to side, and at a uniform pitch from the back of one entrance to the mouth of the adjacent entrance. The arch of the back of each passageway joins the 90 curved cone base of the runner at a sharp angle, as shown in the drawings, but it will be understood that this is for the purpose of clearness of illustration only, and that as actually manufactured, gussets, such as indicated at 55, are inserted to prevent all 95 angles, and to minimize friction. Air striking the base of the runner itself is deflected also in stream-line formation down to the entrance of the passageway and to the inner wall of the other passageway. As shown in 100 the drawings, the inner curve of each passageway wall is a spiral, and is formed by moving the generatrix radially outward from the axis while the conoid is being revolved through slightly more than 180°.

I have purposely spaced the edge of the mouth of the hood, a short distance from the shaft 10, and although it might be thought this would provide a dead air space, such 105 is not the case at all, as the air is moving downwardly at a very rapid rate to replace the air discharged at the peripheral edge. This downwardly moving air is guided by the sharp surface of rotation generated by the sharp angled cusp and the air is thrown 110

directly into the two diametrically opposite hoods where it is whirled through the snail-like passageway and delivered equally through the eight or more orifices. The baffle walls guiding the air to the various orifices not only distribute the air evenly throughout the entire angle of the discharge, but they very efficiently prevent re-entry of the air particularly relatively near each mouth.

In order to prevent loss of air between the housing and the rotary member the latter is provided with the air lock skirt 42 before mentioned and from this skirt 42 there rises an annular vertical flange 58 which fits in a vertical annular slot 60 just beneath the flat top 61 of the housing 62 as best seen in Figure 2. The rim or periphery of the housing extends downwardly from the flat top 61 and again somewhat closely approaches the rotary member or runner. Owing to the abrupt break in the smooth curve of the impeller and also of the housing there is no perceptible loss of air or of pressure at this point.

I claim:

1. In an air transferrer, a rotary element having a plurality of equispaced passageways, a housing, a bearing for said rotary element, a plurality of baffle arms, prime in number with respect to the number of passageways, connecting said housing and bearing.

2. In an air transferrer, a circular runner having a plurality of passageways each greater than 90°, equispaced about a common center, such passageways overlying in part an adjacent passageway and each gradually decreasing in cross-sectional area from its entrance to its exit.

3. A runner having a pair of curved partially overlapping passageways symmetrical arranged about a common axis, each of said passageways being tapered from its entrance to its exit.

4. In an air transferrer, a circular runner having a pair of tapered curved passageways each greater than 90° and each having an entrance lying in a plane radial to the common axis.

5. In an air transferrer, a housing, a runner bearing, an odd number of arms joining said bearing and housing, a runner, a pair of curved tapered passageways having their entrance mouths and discharge orifices diametrically opposite each other.

6. A runner for an air transferrer consisting of a pair of spiral tapered passageways and a partition within each passageway subdividing the fluid passing therethrough.

7. A runner for an air transferrer consisting of a plurality of spaced passageways, each curved on a spiral with respect to their common axes, and each tapered at a uniform

rate from the entrance to the exit thereof, and a sharply pointed conoid directing air into the entrance of each passageway.

8. In a runner for an air transferrer, an air-lock skirt, a plurality of curved tapered passageways, the outer wall of each of which merges into said skirt, and a conoid less in major diameter than the diameter of said skirt, and coaxial with said skirt for discharging air trapped by said passageways.

9. In a runner, a smoothly curved conoid base, a skirt spaced from said base, and a plurality of passageways, each merging into said skirt, and each bounded on its inner side by a spiral curve on the face of said base.

10. In a runner, a curved conoidal base extending unbroken to a peripheral discharge and a pair of curved passageways located on said base on the convex side thereof, said passageways decreasing in height measure parallel to the conoid axis from entrance to exit.

11. In a runner for an air transferrer, a curved conoid having a sharply pointed boss at the center thereof, a pair of hooded passageways diametrically positioned on said base and each spaced from the cusp of said base, whereby air from the intake is thrown to each passageway by the back of the other passageway and by the slope of the said base.

12. In a runner, a smoothly curved conoid, a plurality of curved tapered walls mounted on said conoid to provide a plurality of separated passageways, the inner edge of the mouth of one passageway rising from the back of another passageway wall, and each of the passageway walls at their peripheries merging together to form an annular air-lock skirt spaced from the periphery of said conoid, and vanes between said skirt and said conoid to subdivide the fluid passed through the several passageways.

13. In a runner, a smoothly curved centrally cusped conoid, a pair of curved walls secured to said conoid at one edge only, and forming two tapered curved fluid passageways, the entrance to each lying substantially on opposite sides of said cusp and spaced therefrom, and vanes between said walls and said conoid.

14. In a runner for an air transferrer, a base having a circular periphery, a pair of curved hoods rising from said base and providing two separated passageways symmetrically arranged with respect to the center of the base, the mouth portion of each of said hoods on its center line lying at an angle of 45° to a plane passing through the axis of the runner and the margin of the mouth of the passageway, the back of each of said hoods directing the fluid into the mouth of the other hood.

15. In an air transferrer, a rotary mem-

ber consisting of a base having a circular periphery, an annular skirt, vanes between said base and skirt, and a plurality of arched walls merging into said skirt at their outer edges and rising from said base at their inner edges.

16. In an air transferrer, a bell-shaped rotary element having a plurality of curved passageways, each having at its entrance 10 end an arched mouth, the rim of the mouth lying in radial plane.

17. In an air transferrer, a base having the shape of a surface of revolution and having a cusp at the axis of revolution, a plurality 15 of hoods mounted on said base being joined to the base in a curved line near the axis and being spaced from the base toward the periphery, the space between the base and hoods being the discharge from the device.

18. In an air transferrer, an imperforate circular base having an apex at its axis, a plurality of arched hoods spaced from each other and from the apex of the base, each hood constantly decreasing in height measured 25 parallel to the axis of the base.

19. In a rotary impeller for an air transferring device, a circular base, a plurality of snail-like passageways mounted on the base and spaced therefrom at the periphery of the base to form a discharge portion and a plurality of air diverting walls spaced between the base and the walls of said passageways 30 near the periphery of the base.

20. In an air transferrer, a rotary element, 35 a plurality of bearings for said element, and a plurality of radial arms supporting one of said bearings, said arms being flat in a radial direction in order to baffle the air passing to the rotary element.

21. In an air transferrer, a rotary element, 40 a pair of bearings for said element, one of said bearings being located on the intake side of the element and a plurality of radially disposed flat baffle arms for supporting the bearing on the intake side.

22. In an air transferrer, a circular runner, 45 a plurality of bearings for said runner, one of said bearings being located on the intake side, and a plurality of baffle arms supporting said intake bearing, said arms being flat in a radial plane and being sharpened on the intake side so as to offer little obstruction to air passing parallel to the axis of the rotary element and baffling the air tending to

pass in a direction parallel to the circumference of said element.

23. In an air transferrer a housing, a rotary element for discharging into the housing, a plurality of spiral passageways in said rotary element, each arched in cross-section, 60 a bearing for said rotary element, a plurality of radially disposed flat baffle arms on the intake side of said rotary element, said arms being shaped just to clear the outline of the rotary element and passageways as they revolve, whereby said arms will tend to prevent whirling of the air prior to being taken into the passageways.

24. The device of claim 23 in which the baffle arms are arched and rise from the housing and support said bearing, and fins on 70 said arms between the rotary element and its bearing.

25. In an air transferrer, a stream-line conoid, a plurality of arched snail-shaped 75 passageways secured to said conoid and a skirt on said passageways spaced from and approximately parallel to the peripheral edge of said conoid.

26. In an air transferrer, a housing having a substantially cylindrical but eccentric duct gradually increasing in diameter to its 80 ejection outlet, an impeller having an annular mouth of constant width discharging at all times into said duct, a groove in said housing, a flange on said impeller fitting within said groove and forming therewith an air-lock, and a plurality of deflecting elements in said impeller positioned so that the discharge from the impeller to the duct is 85 approximately constant throughout its entire periphery.

27. In an air transferrer, a housing having a substantially circular duct, circular in cross-section but of constantly increasing 90 size to its discharge end, said duct being open throughout its entire extent forming an annular slot, an impeller consisting of a curved conoid and a plurality of hoods thereon, each hood having a mouth lying in a radial plane, 100 being arched in cross-section and decreasing in height from its entrance to its discharge edge, and means carried by the housing for baffling the air passing to the impeller to prevent the air from whirling prior to entry 105 into said hooded passageways.

In testimony whereof I affix my signature.

JULIUS CLINTON WRIGHT.
